UNITED STATES PATENT OFFICE.

LEO D. JONES, OF PHILADELPHIA, PENNSYLVANIA, ASSIGNOR TO THE SHARPLES SPECIALTY COMPANY, OF PHILADELPHIA, PENNSYLVANIA, A CORPORATION OF DELAWARE.

CENTRIFUGAL SEPARATOR.

Application filed October 7, 1921. Serial No. 506,166.

This invention comprises a mechanism in which the outlet or outlets of a centrifugal rotor are coordinated with a receptacle or receptacles provided with heating means by 5 which a viscous substance or substances separated in the operation can be raised in temperature and fluidity to facilitate its discharge.

Petroleum containing petrolatum or petroleum wax has been successfully treated for the separation of the wax, by chilling the wax bearing oil to precipitate the wax and separating the chilled constituent in a centrifugal rotor containing a carrier liquid, as 10 brine, of greater density than the wax, the wax and the wax freed oil being separately discharged to different receptacles or "covers." The chilled wax, which is kept from contact with the wall of the bowl by 15 the brine, adheres to a greater or less degree to the receptacle or "cover" into which it is discharged, with a tendency to accumulate therein and limit the time during which the operation can be carried on continuously, 20 by reason of the necessity for the removal of such wax.

In accordance with my invention, the separated viscous constituent (particularly the wax separated from petroleum) discharged from a centrifugal rotor is heated and rendered sufficiently fluid to flow by 25 gravity from the "cover" into which it is discharged.

In the preferred practice of my invention 30 as applied to the separation of wax from wax bearing petroleum, the compartment for receiving the wax discharged from the centrifugal rotor is disposed between top and bottom compartments for holding a 35 heating fluid, preferably hot water, and an insulating compartment is provided between the carrier liquid and the adjacent heating compartment.

The invention is comprised in the construction set out in the following description, illustrated by the accompanying drawing.

The drawing is a broken sectional view 40 showing the top of a centrifuge having "covers" providing compartments for receiving the effluents together with compartments for holding a fluid for heating the wax compartment, and a compartment for containing air as an insulating medium be-

tween the brine compartment and the adjacent hot water compartment.

In the drawing, the centrifugal rotor 1 is provided with the neck 2 by which it is suspended and revolved and with the passages 3, 4 and 5 through which the centrifugally separated and stratified constituents are discharged.

In the separation of wax from chilled oil and the use of brine as a carrier liquid, the brine discharged from the rotor flows by 65 way of the passages 3 to the channel 6 and thence over the weir or dam 7, concentric with the axis of revolution; the wax separated from the oil flows from the passages 4 through the chamber 8, over the weir or 70 dam 9 concentric with the axis of revolution, and thence through the passage or passages 10; and the oil freed wax flows by way of the passages 5 to the channel 11 and thence over the weir or dam 12 concentric with the 75 axis of revolution.

A "cover" 13 is supported detachably by the case 14, contains the compartment 15 concentric with the bowl and disposed so as to receive the wax discharged from the passage or passages 10, and has a bottom compartment 16 for containing hot water to heat the compartment 15 through its conical bottom, thereby heating the wax effluent in the compartment and facilitating its discharge therefrom through the spout 17.

The "cover" 18 is supported detachably on the "cover" 13 concentric with the bowl and is provided with the compartment 19 disposed so as to receive the brine discharged over the weir 7. This "cover" has a bottom compartment 20, for holding hot water to heat the compartment 15 with the wax therein, and a compartment 21 between the compartments 19 and 20, for holding air 95 to insulate the compartments 19 and 20, prevent the unnecessary communication of heat to the compartment 19 and conserve such heat for use in the compartment 15.

A "cover" 22 is supported detachably by 100 the "cover" 18, concentric with the rotor, and provides a compartment 23 in position for receiving the oil discharged over the weir 12.

It will now be understood that in the 105 operation of the machine the chilled wax is delivered from the rotor into a heated compartment, with hot top and bottom walls,

and is rendered sufficiently fluid by heat exchange to discharge freely by gravity through the spout 17, the brine and wax freed oil flowing off from their respective compartments 19 and 23 through the respective spouts 24 and 25.

Having described my invention, I claim:—

1. A centrifugal machine comprising a rotor having means for separately discharging constituents of different densities of a substance separated in said rotor, an effluent collector with which a constituent makes initial contact on its discharge from said rotor and over which it flows to a discharge point, and means for maintaining a heating fluid in contact with the exterior of said collector over an area substantially equal to the area of the path of flow of said effluent and heating the collector section with which said constituent makes initial contact.

2. A centrifugal machine comprising a rotor having means for separately discharging constituents of different densities of a substance separated in said rotor, an effluent collector with which a constituent makes initial contact on its discharge from said rotor, and over which it flows to a discharge point, and means for maintaining a heating fluid out of contact with the effluent and in contact with the collector over an area substantially equal to the area with which said effluent makes contact between its discharge from said rotor and its discharge from said collector.

3. A centrifugal machine having, in combination with a rotor provided with outlets for separated constituents, covers provided with compartments for receiving the respective constituents and one or more compartments for holding a heating fluid in contact with a wall or walls of a compartment against which an outlet delivers a constituent.

4. A centrifugal machine having, in combination with a rotor provided with outlets for separated constituents, of covers providing respective compartments in which said outlets discharge, a plurality of said covers having bottom compartments for containing a heating fluid for heating an intermediate compartment and the effluent therein.

5. A centrifugal machine having, in combination with a rotor provided with outlets for separated constituents, of superposed covers having respective compartments reg-

istering with said outlets, the bottom cover having a bottom compartment adapted for holding a heating fluid, and a second cover having a bottom compartment for holding a heating fluid and a compartment for holding an insulating fluid.

6. A centrifugal machine comprising a rotor provided with a discharge passage for an adhesive substance liquefiable by heat and a discharge passage for a liquid, a receptacle to which said rotor directly discharges said substance, means for heating said substance, and means for impeding heat transfer between said heating means and said liquid.

7. A centrifugal machine comprising a rotor provided with a discharge passage for a substance liquefiable by heat and a discharge passage for a liquid, a cover provided with heating means to which said rotor discharges said substance, and an unheated cover insulated from the heat of said cover first named to which said rotor discharges said liquid.

8. A centrifugal machine comprising a rotor provided with a wax discharge port and a liquid discharge port, a heater for heating said wax immediately adjacent to its point of discharge from said rotor, and an unheated receptacle for liquid discharged from said liquid discharge port insulated from said heater.

9. A centrifugal machine comprising a rotor provided with a discharge port for a viscous substance liquefiable by heat, a discharge port for a liquid separated therefrom, and a discharge port for a carrier liquid, a heater immediately adjacent to the point of discharge of said substance from the rotor, and separate receptacles for the reception of the liquids discharged from said rotor, one of said receptacles being interposed between said heater and the other of said receptacles and forming a heat insulator therefore.

10. A centrifugal machine comprising a rotor for separating and separately discharging constituents of a substance, means for heating one of said constituents during the discharge thereof, and means for impeding heat transfer between said heating means and the other of said constituents during the discharge thereof.

In testimony whereof I have hereunto set my name this 4th day of October, 1921.

LEO D. JONES.
